Application May 3, 1948, Serial No. 146,138

Term of patent 14 years

(Cl. D57—1)

To all whom it may concern:

Be it known that we, George P. Geran and Jeremiah F. Toomey, citizens of the United States of America, residing respectively at New York, county of New York, and New York, county of Bronx, State of New York, have invented a new, original, and ornamental Design for a Sunshade or Similar Article, of which the following is a specification, reference being had to the accompanying drawing, forming part thereof.

Figure 1 is a top plan view of a sunshade showing our new design, the head band shown in broken lines in Figure 2 being omitted for convenience of illustration, and

We claim:

The ornamental design for a sunshade or similar article, as shown.

GEORGE P. GERAN.
JEREMIAH F. TOOMEY.
